UNITED STATES PATENT OFFICE

GEORGE DREWES, OF JERSEY CITY, NEW JERSEY, ASSIGNOR OF ONE-HALF TO ADOLPH BERMAN, OF NEW YORK, N. Y.

SLIDING AND SWINGING WINDOW

Application filed October 1, 1929. Serial No. 396,583.

The present invention relates to improvements in double hung sash windows and particularly to that class of windows in which the lower sash is adapted to slide vertically in the window frame and also to be swung inwardly within the room.

An object of this invention is to provide an improved combination vertically sliding and inwardly swinging lower sash which 10 may be placed in a fixed angular position with relation to the upper sash and thus guide the air stream upwardly and prevent the entry of direct drafts incident to the use of the ordinary vertically sliding double 15 hung sash windows.

Another object of this invention is the provision of improved means whereby the lower sash may be connected to hinged guide strips, in order to permit the lower sash and 20 guide strips to be swung jointly inwardly about their lower front edges, thus maintaining an unbroken contact between the sill and the lower sash and preventing any rain from entering the premises at the sill level 25 when the lower sash is swung inwardly within the room.

Another object of this invention is to subdivide the present vertical inner guide strips into two sections, an upper fixed section and 30 a lower pivoted section, and to provide improved locking means for maintaining the upper and lower guide strip sections in fixed vertical alignment, and also for maintaining the lower sash and lower guide strip sections 35 in variable angular relations with the upper sash and thus provide larger or smaller openings for ventilation to suit the convenience of the occupants of the house.

With the above and other objects in view, 40 the invention will be hereinafter more particularly described, and the combination and arrangement of parts will be shown in the accompanying drawings and pointed out in the claims which form part of this specification. It being understood that the embodiment herewith shown is merely illustrative and that various changes in the form, proportion, size and minor details of construction within the scope of the claims may 45 be resorted to without departing from the

spirit or sacrificing any of the advantages of the invention.

Reference will now be had to the drawings, wherein like numerals of reference designate corresponding parts throughout the 55 several views, in which:

Figure 1 is a vertical section through a window casement embodying the present invention, and shows the upper and lower sash in their respective normal closed positions. 60

Figure 2 is a vertical section through the window casement and shows the lower sash swung inwardly.

Figure 3 is a section of the casement and lower sash taken on line 2—2 in Figure 1. 65

Figure 4 is a sectional view of a portion of the fixture used for locking the guide strip sections.

Figure 5 is a sectional view of a portion of a stationary guide strip section, showing 70 a pulley mounted in a recess therein.

Figure 6 is a fragmentary view of the casement, showing the guide strip sections locked for the vertically slid able position of the sash. 75

In the illustrated embodiment of the invention the several views show a transparent glass window pane designated by the number 10, and this pane is secured to the stiles 11 of the lower sash 12, and the upper sash 13, by the usual means well known in the glazing art. 80

As best shown in Figure 3, the stiles 11 are slid able between guide strips 19, 19, and parting strips 15, 15, secured in pairs on the side walls 16, 16, of the window frame. In the usual practice, the side walls are connected at their upper ends to the head of window frame at their lower ends to the sill of the window frame. Normally, the sashes slide vertically and are counterbalanced by means of sash cords 17, 17, at the lower ends of which sash weights are attached. 85

For the purposes of this invention, each 90 guide strip 14 is cut into two separate upper and lower sections 18, 19. The cutting position of the guide strips is designated by the number 20.

The upper section 18 remains fixed to the 100

side wall 16 and the lower section 19 is rockably positioned on hinge means 21, fastened to the sill of the window frame or casement 23 and can swing from the normal vertical position inwardly into the room about their lower front edges as best shown in Figure 2. The form of the cut 20 may be circular and preferably drawn along a radius having the hinge pin as center and the lower guide strip section 19 is made longer than the upper section 18.

Each lower guide strip section 19 is provided with an elongated aperture 24. A guide pin 25 is positioned within the aperture 24 and is secured to the side wall 16.

Each aperture 24 is of the same width as the diameter of the respective guide pin 25, but is about one quarter of an inch longer. When a pair of upper and lower guide strip sections are in vertical alignment, the lower wall of the aperture extends below the guide pin. When the lower guide strip sections are swung inwardly to an inclined position the lower walls of the apertures rise, as best shown in Figure 2, and come in contact with the guide pins and prevent any further movement of the guide strips. The inward swing of the lower guide strip sections is thus predetermined and limited by the guide pins 25.

As best shown in Figure 1, the lower horizontal guide strip 22, has its sash engaging face beveled so as to allow a clearance space for the lower sash to swing inwardly about its lower front edge. This beveled edge 26 extends the full length of the guide strip 22, which remains fixed to the sill and prevents any rain from entering the premises.

The lower guide strip sections 19, 19, carry pivoted hook members 27 which may be rotated so as to engage eye bolts 28 on the lower window sash 12, when the lower sash is at its normal low position. The members 27 and 28 thus form means for connecting the lower sash to the sections 19, 19. When the members 27, 28, are in locked relation and the lower guide strip sections are swung inwardly about the hinges 21 to an inclined position, the lower sash is rocked or swung inwardly about its lower front edges by the hook members 27, 27, and assumes the same inclined position as the lower guide strip sections.

To lock the movable and stationary guide strip sections in fixed vertical position or in fixed angular positions, there is provided a sliding bolt member 29, bolt handle 30, strike plate 31, adjusting screw 32 and a pivoted sleeve member 33 having an aperture 34 in which the bolt 29 is adapted to slide. As best shown in Figure 4, the sleeve member 33 is held in position on the guide strip section 18, by means of a plate 35 to which it is riveted. The plate 35 is fastened to the guide strip in any suitable manner. The

sleeve member 33 rotates freely on the plate 35. These parts 29 to 35 inclusive, in assembled relation comprise one locking fixture 36 which is mounted on each pair of guide strip sections 18, 19.

It is to be noted that the locking fixture 36 functions not only at the extreme vertical and extreme angular position but also at any intermediate angular position, and that the operator is thus able to swing and lock the lower sash so as to provide larger or smaller openings for ventilation, depending on the state of the weather, etc. It is also to be noted that the apertures 24 and pins 25 in the lower guide strip sections may be omitted in some installations and that means for limiting the inward movement of the lower sash may be then provided by the fixture 36 exclusively.

When the lower sash is swung inwardly, the cords 17, 17, tend to rub against the lower edge of the stationary guide strip sections. To prevent damaging the cords and to facilitate their inward angular movement there have been provided pulleys 37 which are suitably mounted at the lower ends of the upper guide strip sections. As best shown in Figure 5 the pulleys are hidden from sight by the upper guide strip sections 18, which have recesses 38 formed therein to receive the pulleys.

A pull handle 39 may be attached to the upper rail of the lower sash and used for grasping the lower sash when swung inwardly.

Operation of invention

When it is desired to swing the lower sash inwardly from a vertically slidable position, the hook and eye members 27, 28 are locked together, the opposite bolt handles 30 are grasped with both hands and the bolts 29 are pulled upwardly until disengaged from the strike plates 31. The bolt members 29 together with the lower guide strip sections 19 are then pulled inwardly. The lower sash 12 being temporarily yieldably connected to the lower guide strip sections by means of the hooks 27 is also swung inwardly and locked in any suitable inclined position by means of the adjusting screws 32 at the will of the operator. The pull handle 39 may also be used to facilitate the locking of the lower sash and lower guide strip sections.

To restore the lower sash to its vertical position, the bolt members 29 are released and the handles 30 are grasped and swung outwardly until the lower sash reaches its vertical limiting position and the bolts 29 are then pulled downwardly into engaging position with the strike plates 31. In this position the upper and lower guide strip sections 18, 19 are locked in vertical align-

ment and the lower sash is then in a vertically slidable position.

When the upper and lower guide strip sections are locked in vertical alignment, direct ventilation may be had by sliding vertically the upper or lower sash or both, and indirect ventilation may be had by swinging the lower sash inwardly about its lower side, and locking the lower guide strip sections 10 and lower sash in angular relation with the upper sash.

Primarily designed for double hung sash windows, this invention utilizes all the guide strips and all other parts presently used 15 on double hung sash. The windows remain in appearance substantially the same as they were before the device is applied. The point of attachment of the cords remains near the top of the sash. It is to be noted that while 20 the device is applicable for installation on new buildings, it may be applied to old buildings by utilizing the old guide strips present on the particular window frame to be equipped for this form of ventilation. 25 The locking fixtures 36 are designed so that both hands are required to release the lower sash and the device is practically inoperable by children.

It is thus readily seen that the objects 30 of the invention are accomplished by means of a novel and practical window construction which may be applied to dwelling houses and other buildings using double hung sash windows.

Having thus described my invention, what 35 I claim as new and desire to secure by Letters Patent is:

1. In a window having a vertically sliding and inwardly swinging lower sash, the 40 combination of rockable guide strips hinged to the sill about their lower front edges and a fixed horizontal guide strip having a sash engaging face projecting upwardly from the sill and being bevelled to allow the 45 inward swing of the lower sash on its lower front edge while said front edge remains stationary in contact with the sill, and yielding means connecting said rockable strips and said sash to cause said sash to follow 50 the movements of the said strips.

2. In a window having a vertically sliding and inwardly swinging lower sash, the 55 combination of rockable guide strips hinged to the sill about their lower front edges and a fixed horizontal guide strip having a sash engaging face projecting upwardly from the sill and bevelled to allow the inward swing of the lower sash on its lower front edge while said front edge remains in its 60 normal vertical sliding plane and stationary in contact with the sill, and yielding means connecting the lower sash to the said rockable guide strips for causing it to follow their movements and non-pivoting pins se- 65 cured to the sides of the window and engag-

ing elongated apertures in the said rockable guide strips to limit their inward swing.

3. In a window having a vertically sliding and inwardly swinging lower sash, the combination of rockable guide strips hinged 70 to the sill and a fixed horizontal guide strip having a sash engaging face projecting upwardly from the sill and bevelled, hook and eye members, connecting the lower sash to the said rockable guide strips for joint inward rotation, non-pivoting pins secured to the sides of the window and engaging elongated apertures in the said rockable guide strips to limit the inward swing of the said 75 guide strips and lower sash to a predetermined maximum, and means for locking the said rockable guide strips and sash in any desired intermediate position.

Signed at Jersey City in the county of Hudson and State of New Jersey this 25th 80 day of July A. D. 1929.

GEORGE DREWES.
